UNITED STATES PATENT OFFICE.

ANDREW G. PAUL AND HERBERT A. JOSLIN, OF BOSTON, MASSACHUSETTS;
SAID JOSLIN ASSIGNOR TO SAID PAUL.

PAPER-DRYING MACHINE.

SPECIFICATION forming part of Letters Patent No. 705,606, dated July 29, 1902.

Application filed June 15, 1893. Serial No. 477,635. (No model.)

To all whom it may concern.

Be it known that we, ANDREW G. PAUL and HERBERT A. JOSLIN, citizens of the United States, residing in Boston, in the county of 5 Suffolk and State of Massachusetts, have invented a new and useful Improvement in Apparatus for Drying Paper, Cloth, and other Articles of a Similar Nature, of which the following is a specification.

This invention is applicable to drying-machines in which the paper or other material to be dried is passed over the surfaces of revolving cylinders, which are heated in any suitable way, as by steam, and in which the 10 material to be dried is pressed against the drying-cylinders by means of a suitable ironer, such as an endless belt of canvas or felt or other suitable material, the ironer being caused to move with the paper and to hold 15 the paper in close contact with the cylinder, thereby becoming an ironer for the paper and preventing the air from getting in between the paper and the drying-cylinder and in which the material to be dried and the ironer 20 are separated between the cylinders and are fed from one cylinder to another on separate feeding or supporting devices. In these drying-machines when the material being dried 25 is brought into contact with the drying-cylinder and forced against that cylinder by the ironing-belt some of the moisture which is 30 expelled from the material is absorbed by the ironing-belt. The ironing-belt is thus more or less wet when it passes away from the first 35 few cylinders. Between the successive drying-cylinders the ironing-belt is run over intermediate rollers. The paper or material to be dried is also passed over intermediate rollers upon its way from one drying-cylinder to 40 the next drying-cylinder. These intermediate rollers have been so arranged that the rollers for the ironing-belt have been below the rollers for the material to be dried. In passing over these intermediate rollers on its 45 way from one drying-cylinder to another the ironing-belt has thus been underneath the material to be dried. As a result of this arrangement the vapor which rises from the ironing-belt while it is passing over the intermediate rollers and between the cylinders 50 rises directly up to the paper or other mate-

rial which is passing over the upper rollers and is absorbed by that material or is deposited on its surface as a coating. This interferes with the drying of the material, as 55 already explained, and is apt to prevent the uniform drying of the same and may cause curling of the material.

One object of our invention is to facilitate the drying of the ironing-belt between successive drying-cylinders—that is, during the time the drying-belt is passing from one drying-cylinder to the next drying-cylinder—and also to prevent any moisture that passes from the ironing-belt at this stage from coming 65 into contact with the material to be dried.

In these machines also the vapor which rises or is driven off from the ironing-belt while it is passing to or around the drying-cylinders naturally rises in the machine and is liable, 70 therefore, to come into contact with some other portion of the ironing-belt, especially that portion which is between the intermediate rollers, and to be reabsorbed by or deposited upon the surface of the ironing-belt at 75 that point. This retards the drying of the ironer and therefore of the paper or other material. Another object of our invention is to prevent this difficulty by removing such vapor or moisture, and thus preventing its reabsorption by or deposit upon any other part 80 of the ironer.

Our invention consists, first, of a suitable air-circulating device, such as is hereinafter described, for removing the vapor or moisture 85 that rises from the ironing-belt while it is passing between the cylinders and for facilitating the drying of the ironing-belt during the time of its passing from one drying-cylinder to another by producing a forced circulation of air over the surface of the ironing-belt or through the ironing-belt itself, whereby the vapor or moisture that rises from the ironing-belt while it is passing between the cylinders is prevented from coming into 95 contact with the material to be dried, and the moisture is more thoroughly, if not completely, removed from the ironing belt between successive heating cylinders, and the ironing-belt is thus more thoroughly dried 100 before being brought again into contact with the material passing through the machine.

Our invention consists, secondly, in suitable apparatus for removing the vapor or moisture that rises from the ironing-belt while it is passing to or around the drying-cylinders, and thus preventing its reabsorption by or deposit upon some other portion of the ironing-belt.

Our invention is fully illustrated in the accompanying drawings, in which—

- 10 Figure 1 is a front elevation of a drying-machine embodying our invention. Fig. 2 is a top or plan view of the same, showing the material broken away. Fig. 3 is a vertical cross-section on the line 3 3 of Fig. 1. Fig. 15 4 is a front elevation of a drying-machine, showing a modification of the invention. Fig. 5 is a top or plan view of the same, showing the material broken away; and Fig. 6 shows another modification of our invention. 20 Similar letters indicate similar parts in the different figures.

Referring to the drawings, *a* is the frame of the machine.

b, *c*, *d*, and *e* are successive drying-cylinders, which are mounted in the machine in the usual way and are adapted to be heated by any appropriate means, as by steam. Cylinders *b* and *e* are shown only in part.

f is the paper or other material that is being 30 dried in the machine.

g is the ironing-belt, which is made of felt or canvas or other suitable material. It is an endless belt made and operated in the usual way.

35 *h h* are rollers for supporting the material to be dried as it passes between adjoining cylinders. *i i* are rollers for supporting the ironing-belt as it passes from one cylinder to the next cylinder. These rollers *h h* and *i i* 40 are mounted in the machine by any suitable means, as by the arms *j*.

k k are rollers for supporting the ironing-belt on its return from the last cylinder to the first cylinder.

45 The parts so far enumerated are all old and their arrangement and operation are well understood, and no claim is made herein to such parts or their combination.

Underneath the ironing-belt between the 50 rollers *i i* the space is shut in by means of walls or side pieces *l l* and a bottom piece *m*, forming a kind of box, which covers and encloses the under side of the ironing-belt at that place. These side and bottom pieces are 55 preferably made of metal. They are constructed so that they come as close to the ironer and the rollers *i i* as possible without touching them. An exhaust-pipe *n* is connected with this box at any suitable or convenient place. In Fig. 1 it is shown as connected with one of these boxes at the bottom and with another box at the side. The pipe *n* is provided with an exhausting device *o*. The exhauster may be of any desired construction—such, for example, as an exhaust-fan. The exhauster is not shown in Fig. 1, but is represented at *o* in Fig. 4.

When the machine is running, the exhauster is put into operation, the air in the inclosed space or box formed by the parts *l l* and *m* is drawn out through the exhaust-pipe *n*, and a current of air is thus drawn through the ironer as it passes between the cylinders. Whatever moisture is given off from the ironer at this place is sucked down into the exhaust-pipe and out through the exhauster. Moreover, this forced circulation of air down through the ironer not only carries with it such moisture as would naturally escape from the ironer at that point, but removes a large 80 part of the moisture which would otherwise remain in the ironer, and thus is an efficient agent in drying the ironer on its passage between adjoining cylinders. The moisture passing off from the ironer is also prevented 85 from coming into contact with the material that is being dried.

In place of the construction shown in Fig. 1 between the cylinders *d* and *e* the construction shown in the same figure between the 90 cylinders *b* and *c* and *c* and *d* may be employed. In this case the side pieces or walls *l l* are made to extend down until they come close to the ironer *g* near the bottom of the machine, as shown at *p*, and they are also 95 continued around the cylinders, as shown at *q*. In this construction the pieces *l l* completely inclose the space between the ironer as it passes over the rollers *i i*, the cylinders, and the ironer as it returns back through the 100 machine. An exhaust-pipe *n* is connected with this inclosed chamber and is provided with a suitable exhausting device. In this construction the moisture is not only removed, as already explained, from the ironing-belt between the rollers *i i*, but it is also 105 removed from the ironing-belt at all points in its passage around the drying-cylinders. The moisture given off from one part of the ironing-belt is in this way prevented from 110 being reabsorbed by or deposited upon some other portion of the same and the drying of the ironing-belt on the cylinders is expedited.

Another form of our improved apparatus is shown in Fig. 4. The ironing-belt between 115 the rollers *i i* is covered or inclosed by a box or partition placed above the ironing-belt instead of below it. This box consists of a top piece *r* and side pieces *s s* and end pieces *t t*. The side pieces extend down close to the ironing-belt. One of the end pieces also extends down close to the ironing-belt. The other end piece extends down about half-way, thus leaving an opening in that end of the box or chamber for the admission of air. The exhaust-pipe *n* is connected with the end of this box opposite the opening. In this construction a constant circulation of air is maintained over the top of the ironing-belt, the moisture rising from the belt is drawn into the exhaust-pipe, and a current of air is also circulated through the ironing-belt, thus removing the moisture more effectually. If desired, both 120 ends of the covering-box may be extended 125 130

down close to the ironing-belt, in which case all the air will be drawn through the belt.

Our improved apparatus produces a forced circulation of air through or over the surface of the ironing-belt, by means of which the moisture which would naturally rise from the ironing-belt is carried off without coming into contact with the material which is being dried or with any other part of the ironer itself, and a very much greater proportion of the moisture is removed from the ironing-belt than if no forced circulation were produced, thus causing the ironing-belt to be effectually dried.

15 The apparatus which we prefer to use is shown in Figs. 4 and 5 of the drawings; but other forms of apparatus can be employed. For example, the diaphragm or partition between the material to be dried and the ironing-belt could be entirely dispensed with and no inclosed box or chamber be used; but a circulation of air could be created and maintained between the material and the ironing-belt sufficient to carry off the moisture from 25 the latter and to prevent such vapor or any material part of it from coming into contact with the material to be dried. This circulation could be produced either by a blowing device serving to blow air between the material and the belt or by an exhausting device serving to suck air between them. Such a blowing device is shown in Fig. 6, in which *w* represents a jet having a long narrow mouth or aperture extending substantially all the 35 way from one roller *h* to the other roller *h*, and *n'* represents a pipe leading from an air-pump or other device for forcing a current of air through the jet *w*.

The advantages secured by our invention 40 are therefore the more thorough removal of the moisture from the ironing-belt, the preventing of the vapor from coming into contact with the material to be dried, the quicker and more economical drying of the material 45 passing through the machine, the reduction of the number of drying-cylinders needed in the machine, the increase in the amount of material that can be dried on a given machine in a given time, the more uniform drying of 50 the material, the prevention of curling of the same, the prevention of the marking of the material by any drops of water that might otherwise be deposited on the bottom of the material and might be pressed between the 55 material and the belt, the saving of steam in the drying-cylinders, and the reduction of the steam-pressure required in the cylinders.

In the old machines the paper or other material was apt to be less thoroughly dried on 60 its under side than on its upper side. This would result in the subsequent curling of the material. Our invention obviates this difficulty.

Having now described our invention, what

we claim as new, and desire to secure by Letters Patent, is—

1. In a drying-machine for drying paper or other material, in combination with revolving drying-cylinders and an ironing-belt moving with the cylinders and suitable means for supporting the material to be dried and the ironer between the drying-cylinders so as to separate them between the cylinders, an air-circulating device for producing a circulation of air close to the ironing-belt whereby the vapor or moisture that rises from the ironing-belt while it is passing between the cylinders is prevented from coming into contact with the material to be dried and the ironing-belt is more thoroughly dried, substantially as set forth.

2. In a drying-machine for drying paper or other material, in combination with revolving drying-cylinders and an ironing-belt moving with the cylinders and suitable means for supporting the material to be dried and the ironing-belt between the drying-cylinders so as to separate them between the cylinders, an exhausting device for producing a circulation of air close to the ironing-belt whereby the vapor or moisture that rises from the ironing-belt while it is passing between the cylinders is prevented from coming into contact with the material to be dried and the ironing-belt is more thoroughly dried, substantially as set forth.

3. In a drying-machine for drying paper or other material, in combination with revolving drying-cylinders and an ironer moving with the cylinders below the material to be dried and suitable means for supporting the material to be dried and the ironer between the drying-cylinders so as to separate them between the cylinders, a box or chamber inclosing or covering the ironer between the cylinders, an exhaust-pipe leading from the box or chamber, and an exhausting device connected with the exhaust-pipe, substantially as set forth.

4. In a drying-machine for drying paper or other material, in combination with revolving drying-cylinders and an ironer moving with the cylinders below the material to be dried and suitable means for supporting the material to be dried and the ironer between the drying-cylinders so as to keep them separate between the cylinders, a box or chamber inclosing or covering the ironer between and upon the cylinders, an exhaust-pipe leading from the box or chamber, and an exhausting device connected with the exhaust-pipe, substantially as set forth.

ANDREW G. PAUL.
